UNITED STATES PATENT OFFICE.

EDWARD J. TOMLINSON, OF EAST ORANGE, NEW JERSEY, ASSIGNOR TO SPLITDORF ELECTRICAL COMPANY, OF NEWARK, NEW JERSEY.

PHONOGRAPH.

Application filed April 7, 1919. Serial No. 288,386.

To all whom it may concern:

Be it known that I, EDWARD J. TOMLINSON, a citizen of the United States, residing at East Orange, in the county of Essex and 5 State of New Jersey, have invented certain new and useful Improvements in Phonographs, of which the following is a specification.

This invention relates to electrically operated phonographs and as illustrated is 10 particularly adapted for playing a record in the form of a flat disk or plate.

It is the principal object of my invention to provide a phonograph in which the 15 sound record body is carried on a support electrically driven in such a manner as to insure a constant speed and quietness of operation. In certain types of motors now in use more or less noise is produced by them 20 which is a detriment to the production of the best results from the playing of the record.

Another object of my invention is to secure the above results with a motor mechanism that is very simple in construction and 25 highly efficient in its operation, consuming a small amount of current. Heretofore it has been customary to use one or more pairs of magnets to act successively on pole pieces 30 attached to the rotating support for the sound record body, but my invention is particularly directed to means for making all 35 of the armature bodies or pole pieces do work simultaneously instead of concentrating this work into a pair of pole pieces.

It is another object of my invention to provide a starting and stopping device for the rotating support which will make the 40 operation of the same substantially automatic during the playing of a record.

Another object of my invention is to provide both a timer and governor simple in construction but highly effective in their operation and disposing these devices so that 45 they may be readily observed for the purpose of inspection and repairs.

Other and further objects will be apparent to one skilled in the art after a study of the specification and drawings annexed thereto, wherein

Figure 1 is a top plan view on a reduced scale of a phonograph without the record disk and with the reproducer part of the tone arm broken away.

Figure 2 is a partial view of Figure 1, on

the same scale, but with the starting and stopping mechanism in the running position.

Figure 3 is a view similar to Figure 2, on the same scale, but showing the tone arm at 60 the end of the playing position and the stopping mechanism in a position similar to that shown in Figure 1.

Figure 4 is a bottom view, on the same scale, of the motor frame shown in Figure 65 1 but with the timer parts removed.

Figure 5 is a view of the timer parts and mechanism not shown in Figure 4, but on an enlarged scale to illustrate them more clearly. This figure also shows the 70 diagrammatic wiring of the motor.

Figure 6 is a part elevation of the phonograph motor.

Figure 7 is a sectional view through the 75 operating electromagnet and core.

Figure 8 is a plan view of the governor device shown in Figure 6 and

Figure 9 is a side elevation of a modified 80 governor device somewhat similar to that shown in Figures 6 and 8.

Figure 10 is a plan view of the stationary 85 base member showing the pole pieces a bracket member and bearing for the rotatable support which is shown in Figure 11.

Figure 11 is a bottom view of the rotatable 85 support.

Figure 12 is a fragmentary section on the line 10—10 of Figure 11.

Figure 13 shows an alternative form of 90 pole piece which may be used in place of that shown in Figure 12.

Figure 14 is a fragmentary bottom view of Figure 13.

Figure 15 is an enlarged view of one of 95 the compound levers shown in Figure 1.

Figure 16 illustrates the type of joint used between the two portions of the compound lever shown in Figure 15, while

Figure 17 shows a detail of one of the members of the other compound lever shown 100 in Figures 1, 2 and 3.

Referring now to the details wherein like numbers refer to corresponding parts in the various views, 1 is a mounting plate having a central opening 2 within which is positioned a base member 3, the same being fastened to the plate 1 through the medium of arms 4 adapted to have screws or bolts pass through the holes 5 in the arms 4. On one side of the plate or base 3 is disposed a set 105 of 110

ries of pole pieces 6 which preferably correspond in number and shape to pole pieces 7 that are carried on the rotatable support member 8. As shown in Figure 12, the pole pieces 6 and 7 are elongated as indicated at 9, in order to present a larger surface for the magnetic flux lines. The type of pole pieces used on the base 3 or as armature bodies 7 on the rotatable support 8, may be 10 of the laminated type as shown in Figure 13 wherein the laminations 10 are arc welded as at 11 to either the base 3 or the support 8. Where the base 3 is made of a casting a central hub 12 is preferably cast integral therewith. The hub 12 serves as a core for a single winding 13. The top of the core 12 is adapted to receive a ball bearing 14, which is also shown in Figure 10, which bearing receives the collar 15 carried on the plate 8, 20 the bearing 14 being held to the core 12 in any suitable manner, such as by screws 16. On the outside of the winding 13 is carried a condenser 17 which will be hereinafter referred to. A sound record support plate is 25 carried on the hub 18 being fastened thereto by any suitable means such as screw 19, a dowel pin 20 being used to prevent the sound record support plate from slipping out of position while the record is being played.

30 As shown in Figure 6, the armature bodies 7 and the pole pieces 6 extend toward each other to a point where a small air gap 21 is obtained. I preferably taper off one corner of the pole pieces 6 as indicated at 22 as I have found in some cases that this assists in quieting the operation of the motor as the flux lines pass through from the pole pieces 6 to the armature bodies 7 or vice versa in a more gradual manner.

40 Mounted on the bottom of the base 3 is a plate 23 having slots 24 therein through which screws 25 pass for the purpose of holding the plate 23 to the base 3. By means of the slots 24 and screws 25, the plate 23 may be adjusted on the base 3 for the purpose of shifting the position of the movable timer member 26 and the stationary adjustable contact 27. The movable member 26 carries a contact 28 that cooperates with contact 27, the other end being turned over as at 29 which turned over portion is engaged by a cam 30 having the same number of indentations therein as there are armature bodies on the rotatable support 8. The cam 30 is held on to an operating shaft in any suitable manner such as a screw 31 and dowel pin (not shown). The operating shaft, it will be understood is attached to the support 8 and passes through the hole 32 in the hub or core 12 and through the base 3, a bushing 33 being preferably used at the timer end to guide the shaft in its operation.

Attached to the base 3 is a lug 34 carrying a pivotal bracket 35 by means of a suitable pivot pin held in the lug 34 in any suitable

manner, such as a cotter pin 36. The bracket 35 carries a sleeve 37 within which a shaft is journaled. One end of the shaft carries a friction wheel 38 that is adapted to run on the periphery of the support 8, being held in 70 engagement therewith, in any suitable manner, such as a spring 39 carried by the base 3. To the other end of the operating shaft is fastened a member 40 which has fingers 41 bent over forming a slot within which the resilient member 42 is seated. On both ends of the member 42 are fastened weights 43 and it will be noted that there is a slight clearance 44 between the weights and the fingers 41 so that the member 42 has a slight 75 longitudinal motion. A contact 45 is carried by the spring member 42 and a cooperating contact 46 carried on an adjustable screw 47 which in turn is supported on an arm 48 that is fastened to the base 3, in any 80 suitable manner, such as a bracket 49. The outer end of the arm 48 is attached to an adjusting screw 50 carried by the arm 48. An adjusting thumb nut 51 is fastened to the outer end of the screw 50 and a spring 52 is 85 adapted to hold the arm 48 in any position to which it is moved by the thumb nut 51 and screw 50. It is seen that the movement of the thumb nut 51 moves the arm 48 to alter the position of contact 46 with reference to the position of contact 45 and it will be further seen that the opening and closing of the contacts 45 and 46 is controlled by the rotation of the governor parts just described. As shown in Figure 9, one set of 90 weights 43 is riveted directly to the members 40 and 42 and only one set of fingers 41 is required on the member 40. This construction is somewhat simpler than that shown in Figures 6 and 8 and functions in substantially the same way.

105 Mounted on the plate 1 but insulated therefrom is a switch blade 53 connected to a terminal stud 54 also a second switch blade 55 in electrical contact with the terminal stud 56. The switch blades 53 and 55 are mounted in such a manner as to be connected together by a switch blade 57 carried on but insulated from one arm 70 of a compound lever, the other arm of which is indicated by 59, this lever being pivoted to the plate 1 by pivot screw 60. It will be observed by reference to Figures 15 and 16 that the arm 59 has a slot 61 therein through which a stud 62, fastened to the arm 58, 110 passes. A lug 63 turned upward on the end of the arm 58 operates in the slot 61 while a second lug 64 of the arm 58 serves as a stop for the lug 65 on the arm 59. From the above description, it will be seen that the arm 59 may be adjusted longitudinally on the arm 58 by loosening the nut 66 and sliding the arm 59 to the desired point where it will engage with pin 67 on the tone arm 68 of the phonograph. The arm 58 has a 115

120

125

130

lug 69 turned upward on its side, which lug engages another portion 70 of the compound lever which carries a stud 71 to which a spring 72 is attached, the other end of the 5 spring being connected to the stud 62 under the nut 66. From this construction, it will be seen that, that part of the compound lever consisting of the arms 58 and 59 is capable of being turned in a clockwise direction 10 about the pivot 60 without moving the arm 70 for a purpose which will be hereinafter explained. A spring 73, having one end fastened to the stud 74 on the plate 1 and the other end to the arm 70, serves to hold 15 the arm 70 in the position shown in Figure 1, wherein the switch blades 53 and 55 are left in open circuit position and a friction block 75, such as a piece of felt, carried on the end of the arm 70 engages the outer 20 periphery of the movable support member 8, as indicated at 76, thereby acting as a brake and stopping the rotation of the member 8.

A second compound lever made up of the members 77 and 78 is used for a purpose 25 which will be hereinafter described. The member 77 is pivoted to the plate 1 by means of a pivot screw 79 passing through the bushing 80. The member 77 is made up of two parts 81 and 82 which are frictionally 30 held in normal working position by the construction of the bushing 80 but on the exercise of considerable force on the member 81, its position with reference to the member 82 may be shifted for a purpose hereinafter pointed out. The end of member 35 82 is slotted at 83 to receive a lug 84 thrown upward on the end of the member 78. The member 78 is pivoted to the plate 1 by means of a slotted pivot 85 through which a spring 40 86 passes. The ends of the spring 86 are fastened to lugs 87 thrown up from the body of the member 78. The outer end of the member 78 has a notch 88 cut therein and a projection 89 that is adapted to engage the 45 cam surface 90 of the member 58.

Coming now to the operation of my device, let it be assumed that the sound record disk has been placed on the rotatable support and that it is desired to start the phonograph, 50 the starting mechanism being in the position shown in Figure 1. Movement of the tone arm 68 carries the pin 67 against the arm 59 of a compound lever and through the medium of lug 69 the arm 70 is carried 55 counter clockwise against the tension of the spring 73 and, due to the frictional engagement at the point 76 of the friction block 75, the rotating support and record disk are given a starting impulse in the proper direction, at the same time the lever 70 is carried to the position shown in Figure 2, at which time the lug 91 on the arm 70 drops into the notch 88 in the member 78 thereby locking the arm 70 in the position 60 shown in Figure 2, in which position the 65 switch blades 53 and 55 are electrically bridged, as shown in Figure 6. This allows current to flow from the battery B to binding post 92 thence through the electromagnetic winding 13 to the contacts 27 and 28 to the frame or ground G, thence through the contacts 45 and 46 of the governor to the binding post 93, through the switch blades 55, 57 and 53 back to the battery B or other source of current. Due to the starting impulse given to the rotating support, as above described, the timer mechanism, hereinbefore described, is brought into operation and opens and closes the circuit through the electromagnet 13 intermittently at the proper intervals to send the magnetic flux through the armature bodies 7 and pole pieces 6 in such a way that torque is produced which rotates the support and the sound record body, the speed of which is controlled by the 70 governor mechanism hereinbefore described and illustrated in Figures 6, 8 and 9. It will be understood that a suitable dust proof cover is used in practice over the timer mechanism but for the sake of clearness it is not 75 shown in the drawings.

As the tone arm 68 moves from the beginning of the playing position to the end of the playing position, the pin 67 engages the member 77 which in turn operates the member 78 to pull the notch 88 out of engagement with the lug 91, thereby releasing or tripping the member 70 which, propelled by the spring 73, is quickly retracted to the position shown in Figure 1, thereby opening the connection between the switch blades 53 and 55 and applying the brake member 75, all as hereinbefore described. When the tone arm 68 is moved back to the position shown in Figure 1, pin 67 will engage the 100 arm 59 but, due to the ability of this arm to move to the right independent of any movement of the rest of the compound lever the pin 67 will finally pass to the position shown in Figure 1 and the arm 59 will be thrown 105 back to its normal position by the spring 72. Should, for any reason at the beginning of the playing operation and after the tone arm and other parts have been carried to a position shown in Figure 2, it be desired to carry 110 the tone arm back, this may be done and the cam surface 90 then engages the projection 89 to move the notch 88 out of engagement with the lug 91, thereby causing a break in the electrical circuit and also applying a 115 brake to the rotatable support.

From what has been said concerning the member 77, it will be understood that the operation of the friction joint between the members 81 and 82 is for the purpose of 120 setting the portion 81 in such a position that pin 67 will engage it at the end of any given record, as records do not always terminate the same distance from the rotating center and at the same place on the record disk. 125 130

This construction of the member 77 therefore, provides means for stopping the phonograph at the end of any record.

In the wiring diagram, shown in Figure 5, it will be noted that the condenser 17 is connected across the timer points 27 and 28 and that a non-inductive resistance R_1 is connected across the governor points 45 and 46, both for the purposes well understood in the art.

While I have shown and described certain details of one form of my invention, I do not wish to be limited to the exact details herein illustrated, as it will be apparent that numerous changes may be made without departing from the spirit of my invention and the scope of the appended claims.

Having thus described my invention what I claim is:

1. In a phonograph, the combination of a rotatable sound record body support, electromagnetic motor means for driving said support, a device controlled by the angular position of said support for energizing said motor means intermittently as the support rotates, means constructed and arranged to be operated by the phonograph tone arm and when moved to playing position for giving the rotating support a starting impulse to insure the operation of said device in energizing the motor means intermittently and for closing a break in the circuit through said motor means.
2. In a phonograph, the combination of a rotatable sound record body support, electromagnetic motor means for driving said support, a device controlled by the angular position of said support for energizing said motor means intermittently as the support rotates, means constructed and arranged to be operated by the phonograph tone arm when moved to playing position for giving the rotating support a starting impulse to insure the operation of said device in energizing the motor means intermittently and for closing a break in the circuit through said motor means, and further means operated by the tone arm at the end of the playing position for effecting a break in the motor circuit and subsequently to apply a brake to the rotatable support to stop it.
3. In a phonograph, the combination of a rotatable sound record body support, electromagnetic motor means for driving said support, a device controlled by the angular position of said support for energizing said motor means intermittently as the support rotates, means constructed and arranged to be operated by the phonograph tone arm when moved to playing position for giving the rotating support a starting impulse to insure the operation of said device in energizing the motor means intermittently and for closing a break in the circuit through said motor means, and further means oper-
- ated by the tone arm at the end of the playing position for tripping the first mentioned means from its position set by the tone arm to cause said means to effect a break in the motor circuit and apply a brake to the rotating support.
4. In a phonograph, the combination of a rotatable sound record body support, electromagnetic motor means for driving said support, a device controlled by the angular position of said support for energizing said motor means intermittently as the support rotates, means consisting of a compound lever, in which one part is capable of movement in one direction independent of movement of the rest of the lever and which first mentioned part is constructed and arranged with respect to the rest of the lever so that; when acted on by the phonograph tone arm when moved to playing position it moves the rest of the lever to cause the same to give the rotating support a starting impulse and to close a break in the electrical circuit through said motor means; and when acted on by the tone arm in being moved to inoperative position it trips the rest of the lever to open said circuit and brake the rotating support.
5. In a phonograph, the combination of a rotatable sound record body support, electromagnetic motor means for driving said support, a device controlled by the angular position of said support for energizing said motor means intermittently as the support rotates, means consisting of a compound lever having one portion constructed and arranged so that when acted on by the phonograph tone arm, in being moved to playing position, the rest of the lever is caused to give the rotating support a starting impulse and to close a break in the circuit through the motor means.
6. In a phonograph, the combination of a rotatable sound record body support, electromagnetic motor means for driving said support, a device controlled by the angular position of said support for energizing said motor means intermittently as the support rotates, means consisting of a compound lever having one portion constructed and arranged so that when acted on by the phonograph tone arm, in being moved to playing position, the rest of the lever is caused to give the rotating support a starting impulse and to close a break in the circuit through the motor means, and a second lever, constructed and arranged so as to be acted on by the tone arm when it reaches the end of the playing position for tripping the first lever so it will open the said circuit and brake the rotatable support.
7. In a phonograph, the combination of a rotatable sound record body support, electromagnetic motor means for driving said support, a device controlled by the angular

- position of said support for energizing said motor means intermittently as the support rotates, means consisting of a compound lever having one portion constructed and arranged so that when acted on by the phonograph tone arm, in being moved to playing position, the rest of the lever is caused to give the rotating support a starting impulse and to close a break in the circuit through the motor means, and a second compound lever having, one portion constructed and arranged to lock that part of the first mentioned lever which closes the said circuit when said part has been moved to said closed position; and another portion constructed and arranged to be acted on by the tone arm when it reaches the end of the playing position for operating the first portion to trip its lock with the first mentioned lever whereby the said lever moves to open said circuit and brakes the rotatable support. 45
8. In a phonograph, the combination of a rotatable sound record body support, electromagnetic motor means for driving said support, a device controlled by the angular position of said support for energizing said motor means intermittently as the support rotates, means consisting of a compound lever having one portion constructed and arranged so that when acted on by the phonograph tone arm, in being moved to playing position, the rest of the lever is caused to give the rotating support a starting impulse and to close a break in the circuit through the motor means, and a second compound lever having, one portion constructed and arranged to lock that part of the first mentioned lever which closes the said circuit when said part has been moved to said closed position; and another portion having two members capable of relative adjustment for varying the time of engagement by the phonograph tone arm whereby the action of the tone arm on the member engaged by it moves the other of said two members so as to move the trip portion of the second compound lever so that the said lever held in locked position is released and opens the circuit and brakes the rotatable support. 55
9. In a phonograph, the combination of a 50 rotatable sound record body support, electric motor means for driving said support, a tone arm, a lever operated by the tone arm for giving an initial start to the said rotatable support and for closing the motor 55 circuit and a second lever operated by the tone arm for tripping the first mentioned lever to open the motor circuit and apply a brake to the rotatable support. 55
10. In a phonograph, the combination of a 60 rotatable sound record body support, electric motor means for driving said support, a tone arm, a lever operated by the tone arm for giving an initial start to the said rotatable support and for closing the motor 65 circuit, a second lever for locking the first lever in circuit closing position and adapted to be acted on by the tone arm to trip the first mentioned lever for opening the circuit and applying a brake to the rotatable support. 70
11. In a phonograph, the combination of a 75 rotatable sound record body support, electric motor means for driving said support, a tone arm, a lever operated by the tone arm for giving an initial start to the said rotatable support and for closing the motor circuit, a second lever for locking the first lever in circuit closing position, said second lever having a portion adjustable to suit the path of travel of said tone arm, said tone arm acting on the second lever to trip it from engagement with the first mentioned lever as and for the purpose described. 80

In witness whereof, I affix my signature. 85
EDWARD J. TOMLINSON.
